FIG. 1

FIG. 2

FIG. 3

FIG. 4

FIG. 5

FIG. 6

FIG. 1 is a front, top and right side perspective view of a combined electric phonograph, cassette recorder and reproducer and radio or similar article, showing our new design in assembled position;

FIG. 2 is a top plan view;

FIG. 3 is an exploded left side, top and front perspective view with the cover removed;

FIG. 4 is a front elevational view with the cover removed and omitted for convenience in illustration;

FIG. 5 is a right side, top and rear perspective view with the cover removed and omitted for convenience in illustration; and

FIG. 6 is a left side elevational view thereof with the cover removed and omitted for convenience in illustration.

Portions of the drawing figures are shaded to indicate contrast in appearance, and portions are diagonally lined to indicate transparency. Portions which would be visible through the transparent cover in FIGS. 1 and 2 have been omitted for convenience in illustration.

We claim:

The ornamental design for a combined electric phono-

graph, cassette recorder and reproducer and radio or similar article, as shown and described.
